POOLSIDE SKIMMER

Sidney Sandler, 310 E. 44th St., Manhattan, N.Y.

Filed Oct. 29, 1962, Ser. No. 72,293

Term of patent 3½ years

(Cl. D9—6)

FIG. 1 is a side elevational view of a poolside skimmer showing my new design;

FIG. 2 is a top plan view of said poolside skimmer;

FIG. 3 is a bottom plan view of said poolside skimmer;

FIGS. 4 and 5 are, respectively, rear and front end views of said poolside skimmer on a reduced scale; and

FIG. 6 is a cross-sectional view taken longitudinally through the center of the article shown in FIG. 3.

I claim:

The ornamental design for a poolside skimmer, substantially as shown.
